BY George Cook,
ATTORNEY.

UNITED STATES PATENT OFFICE.

ADOLPH LUDWIG, OF BROOKLYN, NEW YORK.

DESIGN FOR A TRAY OR RECEPTACLE.

SPECIFICATION forming part of Design No. 21,621, dated June 14, 1892.

Application filed May 12, 1892. Serial No. 433,221. Term of patent 7 years.

To all whom it may concern:

Be it known that I, ADOLPH LUDWIG, a citizen of the United States, residing at Brooklyn, in the county of Kings and State of New York, 5 have invented and produced a new and original Design for Receptacles, and more particularly to trays and receptacles for containing bread, cake, &c., of which the following is a specification, reference being had to the accompanying drawings, forming part thereof.

Figure 1 is a plan view of a tray, showing my design. Fig. 2 is a perspective view of the same. Fig. 3 is a sectional view taken on the line 3 3 of Fig. 1.

15 The leading feature of my design consists in the waving or undulating surface of the surrounding sides of the article produced by forming said sides with the rounded and in-

wardly-extending knolls A B and the ends with like formations C. The sides of the article are also bent over and outwardly, as shown, the surrounding edge having the contour, as shown in Figs. 2 and 3, and ornamented as desired, as indicated at D. This tray is designed more especially to be made 20 of silver, but of course can be formed of other materials. 25

Having fully described my invention, what I claim as new, and desire to secure by Letters Patent, is—

The design for trays or receptacles, as herein shown and described.

ADOLPH LUDWIG.
